ELECTROLYTIC PROCESS FOR PRODUCING
PHOSPHINE

George T. Miller, Lewiston, N.Y., assignor to Hooker Chemical Corporation, Niagara Falls, N.Y., a corporation of New York

Filed Mar. 4, 1963, Ser. No. 262,496
8 Claims. (Cl. 204—101)

This invention relates to a process for the preparation of phosphine. More particularly, it relates to electrolytic processes for the preparation of phosphine, including suitable apparatus for effecting such processes.

In preparing phosphine electrolytically, molten phosphorus reacts with hydrogen gas or ions being produced at one of the electrodes in the cell to yield phosphine, one of the desired products. Other end products are also obtainable, depending on the electrolyte utilized in the cell. During the usual operation of such cells, it has been observed that the phosphorus is not consumed completely and becomes viscous after a period of time. When this occurs, it is the phosphorus that is replenished or replaced because the viscous phosphorus reduces the efficiency of the cell and decreases the yield of phosphine. The process and apparatus of the present invention provides for an efficient utilization of phosphorus and greatly increases the yield of phosphine therefrom.

It has been found by the present invention that in the electrolytic cells herein described that phosphorus will remain in a non-viscous state when it is purged with a reducing gas. In accordance with this invention, phosphine may be prepared by contacting an anode and a cathode with an electrolyte, a portion of said cathode being in contact with phosphorus, maintaining a layer of phosphorus on a surface of said cathode, maintaining an electric current between said anode and said cathode through said electrolyte, and purging said phosphorus with a reducing gas, so that the phosphorus is maintained in a non-viscous form and phosphine is recovered in the region of the cathode.

It has been also found that when the reducing gas is passed through the phosphorus of an electrolytic phosphine cell, the phosphorus contained therein more readily proceeds up and remains in contact with the cathode, to maintain a thin layer of phosphorus on the surfaces of the cathode. It has been also found that the required current density in the cell is increased, thereby allowing a decrease in electrical power consumption, producing a high yield of phosphine.

An electrolytic cell that has been found successful in carrying out the operation of this invention comprises an anode and cathode, an electrolyte in operative relationship with the anode and cathode, liquid phosphorus in contact with said cathode so that by passing an electric current through the electrolyte phosphine is generated in the catholyte gas, and means for passing a gas through the phosphorus to maintain it in a non-viscous condition. Of course, there must be a source of hydrogen for phosphine production and this may be an aqueous electrolyte or one otherwise capable of yielding hydrogen to react with the phosphorus.

The various aspects of the invention will be apparent from the following description, taken with the drawing illustrative of an embodiment of the invention, in which FIG. 1, is a central vertical sectional view of the apparatus of this invention along 1—1, and FIG. 2 is a horizontal sectional view along 2—2.

Referring to FIG. 1, cell vessel 10 contains anode compartment 12, anode 14, cathode compartment 16, and cathode 18. A porous or permeable diaphragm 20 separates anode and cathode compartments and separates the

2

electrolyte into anolyte 17 and catholyte 19 sections. Phosphorus 24 in a liquid state is present in the cathode compartment 16. Diaphragm 20 is covered or coated on the side thereof facing the liquid phosphorus, where it may otherwise contact the phosphorus, with a coating, cover or sheath 22, against which phosphorus does not adhere, so that it does not wet the diaphragm, which action is evidenced by convex meniscus 21. Ports 26 and 28 permit the addition and removal, either continuously or batchwise, of anolyte from anode section 12. Ports 30 and 32 permit the addition and removal, either continuously or batchwise, of catholyte from the cathode section 16. Port 34 permits the addition and removal of phosphorus from a cathode section 16. Sufficient phosphorus 24 is added to the cathode compartment 16 to contact the lower portion or edge of cathode 18, permitting contact of the phosphorus with a greater surface of the cathode by a wetting action. Anolyte gas discharge port 36 is provided in the top of the anode section 12 to remove anolyte gas from the electrolytic cell. Catholyte gas discharge port 38 is provided on the top of cathode section 16 to remove catholyte gas. Gas-liquid interfaces are indicated at 15. Conduit 60 carries the catholytic discharge gas to gas-liquid separator means 62, which may be a condenser, centrifuge or other suitable apparatus. Here the gas and liquid electrolyte, which may be carried over, are separated. The liquid phase 19 is returned to the electrolyte 19 in the cell by conventional return means or pipe 61. Conduit 64 carries the catholyte gas to condenser 66, where some of the electrolyte which has come over in a gas phase may be condensed and returned to the cell 10. Uncondensed gases principally phosphine are then delivered through conduit 68 to pump 70 or to a storage area or other suitable receiver. Generally, only a minor proportion of the catholyte gas is shunted through conduit 68 to be recycled through conduit 72 via pump 70 through port 73 and into the phosphorus 24 at 74.

Electrolyzing current to the electrodes is transmitted by anode electrical cable or connector 46 and cathode electrical cable or connector 48, joining the anode and cathode to the positive and negative poles at plugs 42 and 43, respectively, of a source of direct current 50.

If desired, a heating or cooling means such as a constant temperature bath, not shown, may be employed to maintain the cell at or near a desired operating temperature.

Cell vessel 10 may be constructed of any material capable of resisting corrosion by the electrolyte and other materials employed in the cell. Typical examples of suitable materials of construction for cell vessel 10 include glass, glazed ceramics, tantalum, titanium, hard rubber, polyethylene, rigid materials coated with phenol-formaldehyde resin and the like.

The purging gas of this invention may be any suitable reducing type gas. Suitable reducing gases include hydrogen, phosphine, hydrogen sulfide, carbon monoxide, hydrogen cyanide, saturated and unsaturated hydrocarbon gases, such as ethane, methane, butane, butene, acetylene gases, and other natural fuel type gases and mixtures thereof. The gases herein may be delivered from an external or internal source through conduit 72, purge the phosphorus, and leave through port 38. It is highly preferred that a portion of the cathodic gas is recycled to purge the phosphorus. The rate at which this gas is delivered to the phosphorus may vary from between about 0.5 liter and 100 liters per hour per square foot of cathode area. However, between about 0.5 liter and 25 liters per hour per square foot of cathode are preferred. However, best results are achieved using between about 1 and 20 liters per hour per square foot of cathode area. Of course other proportions may be used, but the operation in such cases usually will not be as successful. The pro-

portion of cathode gas which may be recycled may vary between about 10 and 90 percent of the total gas produced at the cathode. The preferred amount of cathode gas which may be recycled is between about 60 and 75 percent of the total cathode gas. However, optimum results are obtained when between about 25 and 35 percent of the cathode gas is recycled. The purging of phosphorus with a reducing gas preferably by recycling of the catholyte gases, results in a manifold benefit for the production of phosphine. An increased current density results at the cathode, the phosphorus utilized in the production of phosphine in the cell may be maintained within the cell for a longer period of time, thus yielding more phosphine per unit of phosphorus placed in the cell, and phosphorus is made to contact the cathode more efficiently due to the formation of phosphorus droplets as films which adhere and climb or "wick-up" the cathode surface more readily.

Although the exact mechanism of the action of the gas is not known, it is believed that the gas utilized to purge phosphorus should be one which prevents phosphorus hydrates from forming. However, this invention is not intended to be limited by this disclosed possible mechanism.

The viscosity of elemental phosphorus is about 1.55 centipoises measured at about 50 degrees centigrade. When the viscosity of the phosphorus in the cell is about 8 or 9 centipoises at 50 degrees centigrade, the cell efficiency is reduced to such a level that the phosphorus should be replenished for efficient operation. It has been found that by blowing, purging, agitating, circulating, bubbling, or reducing the pool of phosphorus with a reducing gas, the viscosity is usually maintained between 1.6 and 4.5 centipoises. Very favorable results also are obtainable when the viscosity is maintained at between about 1.55 and 7 centipoises by a reducing gas, all measurements being taken at 50 degrees centigrade on an Ostwald-Fenshi type viscometer.

Diaphragm 20 which separates the anode section 12 from cathode section 16, may be a porous or semipermeable material resistant to the cell contents and capable of maintaining the anode and cathode gases separate, but allowing the electrolyte to pass through. The phosphorus is also held in the catholyte section of the cell. Typical examples of suitable materials for use as a diaphragm include porous Alundum, porous porcelain, resin impregnated wool felt, and various other separators of the types which may be normally employed in the lead storage batteries.

Solid materials having a hydrogen overvoltage, as normally measured in the absence of phosphorus, exceeding the hydrogen overvoltage of smooth platinum may be desirably employed as the cathode. Typical cathodic materials include lead, amalgamated lead, cadmium, tin, aluminum, nickel, alloys of nickel, such as "Mu Metal" (an alloy containing 77.2 percent nickel, 4.8 percent copper, 1.5 percent chromium, and 14.9 percent iron), Monel, copper, silver, bismuth, and alloys thereof. For example, lead-tin, lead-bismuth, and tin-bismuth alloys may be employed. Various shapes of cathodes may be employed. For example, the cathode may be a plate as illustrated in the drawing. Mats of metallic wool and porous metal sheets may also be employed if desired. It is also suitable to utilize a liquid molten mercury cathode in the practice of the present invention.

Suitable anode materials include lead, platinum, lead peroxide, graphite and other materials of construction capable of conducting current and resisting corrosion under the conditions of electrolysis employed.

In one embodiment of the invention, a lead plate with grooves is employed as the cathode and a graphite plate is employed as the anode. Under these conditions, it has been found that the wicking effect of the lead cathode is markedly improved.

The electrolyte may be a salt or other organic or inorganic electrolyte which is non-reactive with molten phosphorus and which is capable of forming hydrogen gas or ions under the electrolytic conditions employed. Typical examples of suitable compounds in aqueous solution, which may be employed as the catholyte include hydrochloric acid, sodium chloride, lithium chloride, potassium chloride, sodium sulfate, potassium sulfate, monosodium-phosphate, disodiumphosphate, acidic acid, ammonium hydroxide, phosphoric acid, sulfuric acid, and mixtures thereof. The concentration of a compound in the aqueous electrolyte may vary from about 1 to about 95 percent, but is usually between about 5 and about 80 percent, and is preferably between about 10 and about 50 percent. Suitable non-aqueous electrolytes may also be employed in the present invention, e.g., sodium hydride.

Improved results have been obtained when metallic ions are present in the electrolyte in small proportions.

Suitable concentrations of the metal ions may be between about 0.01 and 5 percent by weight of the electrolyte. However, between about 0.02 percent and 3 percent by weight of electrolyte may also be utilized. Preferably though, between about 0.02 and 15 percent by weight of electrolyte may be utilized. For example, ions of metals such as antimony bismuth, lead, tin, cadmium, mercury, silver, zinc, cobalt, calcium, barium, and mixtures thereof may be employed. The metal ions may be placed in the electrolyte by employing a consumable anode of the desired metal or metals such as a lead anode, whereby metal ions are formed in the catholyte and transferred to the area adjacent to the cathode. Salts or other compounds of the metals such as chlorides, phosphates, acetates, and the like may be dissolved in the electrolyte if desired. In another embodiment, finely divided metal in elemental form is dissolved in the electrolyte.

During electrolysis, the temperature of the catholyte and anolyte should be maintained above the melting point of phosphorus (about forty-four degrees centigrade), and below the boiling point of the electrolyte. Temperatures between about sixty degrees centigrade and one hundred and ten degrees centigrade are generally satisfactory, but optimum yields of phosphine are obtained at temperatures between about seventy degrees centigrade and about one hundred degrees centigrade. When an electric current is passed through the cell, molten phosphorus on the surface of the cathode is consumed in the formation of the catholyte gas in the cathode section. The catholyte gas is predominantly phosphine, but contains some hydrogen. A portion of this gas may be recycled and passed through the phosphorus in the cell. The anolyte gas composition depends on the overvoltages of the anions in the anolyte with reference to the anode material, as well as on the electrolyte. Thus, for example, the anolyte gas predominates in oxygen if sulfuric acid or phosphoric acid is utilized with a platinum anode, whereas for the same anode, chlorine predominates if hydrochloric acid is used as an anolyte. Thus, the coproduction of anodic oxidation products may be carried out in the anode compartment of the cell of this invention without departing from the spirit of the invention.

The phosphine-containing gas produced at the cathode has a relatively high concentration of phosphine usually more than 60 percent, and it may be as high as 90 percent phosphine by volume or higher. The catholyte gas is substantially free from other phosphorus hydrides.

The following examples are presented to illustrate the invention further, without limiting it. All parts in the specification, examples and claims are by weight and all temperatures are in degrees centigrade, unless otherwise specified.

Example 1

Liquid phosphorus (40 parts) was charged to an electrolytic phosphine cell. The cell contained a lead cathode and a graphite anode. The electrolyte in the cell consisted

of 10 percent hydrochloric acid with about 0.04 percent finely divided elemental lead, dissolved therein. The cell was divided into anolyte and catholyte sections by an Alundum diaphragm coated with glass fabric.

After addition of liquid phosphorus to the cell, direct current was applied to the cell at a potential of 4 volts. At the beginning of the cell operation, the cathodic gas was analyzed for phosphine gas and was found to be 30 to 40 percent phosphine. After seven days continuous operation (about 326 ampere-hours) the phosphorus in the cell had become viscous (over 8 centipoises) and an analysis of the catholyte gas showed that only about 8 percent phosphine was present. This operation was without benefit of circulation or recycling of reducing gas through the phosphorus.

Example 2

Additional melted phosphorus (60 parts) at 50 degrees centigrade was added to the phosphine producing cell of Example 1. Operating conditions were kept the same except for the use of hydrogen gas to treat or purge the phosphorus. This cell was operated for seven consecutive days with intermittent analyses of the catholyte gas. Over this period of time, the liquid phosphorus did not become viscous and analyses of the catholyte gas showed between 25 70 and 75 percent phosphine present in the cathode gas.

Example 3

Phosphorus was added to the cell and Example 2 was repeated except that about 40 percent of the cathode gas was recycled to purge the phosphorus, and no extra hydrogen was used. After 24 hours, the recycling of the catholyte gas was stopped and the cell continued in operation. The percent of phosphine in the cathode gas, without passing recycled cathode gas into the cell, was then analyzed over a period of about an hour, as indicated in Table I.

TABLE I

Time in minutes:	Percent phosphine present	40
0	84	
5	87	
10	86.5	
17	85	
22	83	
38	79.5	45
55	69	

After 1 hour, about 50 percent of the cathodic gas was again recycled. Table II indicates the results of subsequent analyses:

TABLE II

Time in minutes:	Percent phosphine present	50
8	73	
21	75.5	

Example 4

Phosphine was prepared utilizing the apparatus and process of Example 3, except that the rate at which the cathode gas was recycled was varied. Each test was carried on for a period of 24 hours. The variations in the rates of recycling and the percentages of phosphine in the cathode gas are given in Table III.

TABLE III

Recycle Rate Liters per Hour per Square Foot of Cathode	Average Percent Phosphine in Cathode Gas
2	77
7	80
11	85
15	92
26	85
16	90

Although the recycle of produced or external gas through the reactive material has been described with respect to treating phosphorus in the electrolytic manufacture of phosphine, it should be clear that such gas treatment will also be useful when other reactive materials, e.g., sulfur, are to be kept fluid and are to be aided in wetting an electrode at which they react with electrolytic products. Also considered as within the inventive concept are processes in which phosphorus is reacted with an electrolytic cell to produce materials other than PH_3 .

5 The invention has been described with respect to a preferred embodiment thereof. It is not limited thereto, but also encompasses apparatuses and processes in which equivalents have been substituted for the elements of the 10 appended claims.

15 What is claimed is:

1. A process for preparing phosphine electrolytically comprising:

- (a) contacting an anode and a cathode with an electrolyte, a portion of said cathode being in contact with a body of liquid phosphorus;
- (b) maintaining a layer of said phosphorus on the surface of said cathode;
- (c) maintaining an electric current between said anode and said cathode through said electrolyte;
- (d) and passing a reducing gas into contact with and through said body of phosphorus so that it is maintained in liquid form and phosphine is produced in the region of the cathode.

20 30 A process in accordance with claim 1 wherein the reducing gas is selected from the group consisting of hydrogen, phosphine, hydrogen sulfide, carbon monoxide, hydrogen cyanide, saturated and unsaturated hydrocarbon gases and mixtures thereof.

35 3. A process in accordance with claim 1 wherein the reducing gas is a mixture of hydrogen and phosphine.

4. A process for preparing phosphine electrolytically comprising the steps of:

- (a) contacting an anode and a cathode with an electrolyte, a portion of said cathode being in contact with a body of liquid phosphorus;
- (b) maintaining a layer of said phosphorus on the surface of said cathode; and said cathode through said electrolyte, whereby a gas comprising hydrogen and phosphine is produced at the cathode; and
- (c) passing an electric current between said anode;
- (d) recycling a portion of the gas produced at the cathode through the body of phosphorus in contact with the cathode so that it is maintained liquid.

50 5. A process in accordance with claim 4 wherein the gas produced at the cathode is recycled at a rate of from between about 0.5 and 100 liters per hour per square foot of cathode.

55 6. A process in accordance with claim 4 wherein the phosphorus is maintained at a viscosity between about 1.55 and 7.0 centipoises measured at 50 degrees centigrade.

7. A process in accordance with claim 1 wherein the cathode is lead.

8. A process in accordance with claim 1 wherein the electrolyte is capable of forming hydrogen gas under the electrolytic conditions employed.
